(57) **CLAIM**

The ornamental design for a “combination wet/dry vacuum cleaner,” as shown and described.

DESCRIPTION

FIG. 1 is a left side perspective view of a combination wet/dry vacuum cleaner showing our new design;

FIG. 2 is a front elevational view thereof;

FIG. 3 is a rear elevational view thereof;

FIG. 4 is a left side elevational view; the right side elevational view being a mirror image thereof; and,

FIG. 5 is a top plan view thereof.

The details shown in broken lines are for illustrative purposes only and form no part of the claimed design.
